UNITED STATES PATENT OFFICE.

HENRY RINGLER AND HANS WILKINS, OF PITTSBURGH, PENNSYLVANIA.

DETACHABLE RUBBER HEEL.

Application filed November 1, 1924, Serial No. 747,242.

This invention relates to improvements in detachable rubber heels for shoes and has for its principal object to provide a means for securing the rubber heels on a pair of shoes against accidental disengagement therefrom.

A further object of the invention is to provide a detachable rubber heel of the above mentioned character, wherein means is associated therewith for facilitating the removal of the rubber heel from the heel of the shoe after the same has become worn and of no further use.

A further object is to provide a detachable rubber heel of the above mentioned character, which is simple in construction, inexpensive, strong and durable and furthermore adapted for the purposes for which it is designed.

Other objects and advantages of this invention will become apparent during the course of the following description.

In the accompanying drawing forming a part of this specification and in which like numerals designate like parts throughout the same:

Figure 1 is a side elevation of the device embodying our invention.

Figure 2 is a sectional view taken approximately on line 2—2 of Figure 1.

Figure 3 is a top plan view of the detachable rubber heel.

Figure 4 is a bottom plan view of the heel of the shoe, and

Figure 5 is a detail perspective view of one of the T-shaped members.

In the drawing, wherein for the purpose of illustration is shown the preferred embodiment of our invention, the numeral 1 designates the leather heel of a shoe. Secured to the bottom of the leather heel 1 is the metallic plate 2, the securing means therefor being illustrated at 3. A pair of inverted substantially T-shaped members such as is shown at 4 with reference more particularly to Figure 5 of the drawing extend longitudinally on the bottom of the metallic plate 2 and are secured thereon by the fastening elements 5. The purpose of the inverted T-shaped members will hereinafter be more fully described.

Embedded in the rubber detachable heel 6 is a metallic plate 7 and the same supports a pair of longitudinally extending channel shaped members 8, the upper faces of which are open for cooperation with the inverted T-shaped members 4, whereby the

rubber heel 6 may be held in locked engagement with the leather heel 1. The upper portion of the channel members 8 lie substantially flush with the cut out portion 9 provided in the top of the rubber heel 6 to accommodate the metallic plate 2 so that a snug fit between the rubber heel and the leather heel is formed as clearly illustrated in Figure 2. Disposed within the rear portions of the channel members 8 are the coil springs 10 and the purpose thereof will be hereinafter more fully described. A flat spring such as is shown at 11 is secured to the inner side of each of the channel members 8 and extends longitudinally thereon, the forward end of the springs being bent laterally to provide a tongue 12 which is disposed over the forward end of each of the channel members as clearly illustrated in Figure 3.

In attaching the rubber heel 6 to the leather heel of the shoe, the tongues 12 formed on the forward ends of the flat springs 11 are moved out of engagement with the forward ends of the channel members so that the tapered ends 13 of the T-shaped members 4 secured to the plate 2 enter the forward ends of the channel members and by sliding the rubber heel forwardly, the T-shaped members 4 will be guided in the channel members 8 until the outer edge of the rubber heel is flush with the outer edge of the leather heel. This will cause the tapered ends of the T-shaped members 4 to twist the coil springs 10 and normally hold the same under tensions. The spring tongues 12 will also extend over the forward ends of the T-shaped members 4 thereby preventing the longitudinal sliding movement of the rubber heel with respect to the leather heel. In this manner the rubber heel will be securely supported on the leather heel of a shoe against accidental disengagement therefrom.

When it becomes necessary to remove the rubber heel from the leather heel of the shoe after the same has become worn, the tongues 12 are moved out of engagement with the forward ends of the T-shaped members, and the coil springs 10 will force the rubber heel rearwardly so that the same may be easily and readily removed from the leather heel.

While we have shown the preferred embodiment of our invention, it is to be understood that various changes in the size, shape and arrangement of parts may be resorted to

without departing from the spirit of the invention, and the scope of the appended claims.

Having thus described the invention, what we claim is:—

1. A detachable rubber heel comprising in combination with a metallic plate adapted to be secured to the leather heel of a shoe, inverted substantially T-shaped members secured to the bottom of said plate, channel members in said rubber heel adapted to slidably receive the T-shaped members, means for preventing the accidental displacement of the rubber heel from the leather heel, said means comprising a flat spring secured to the side of each of the channel members, the forward end thereof being disposed laterally to provide a tongue adapted for engagement with the forward ends of the respective T-shaped members, and means in the opposite ends of the channel members for facilitating the detaching of the rubber heel from the leather heel when said tongues are moved out of engagement with the forward ends of the T-shaped members, said last mentioned means comprising coil springs disposed in the rear ends of the channel members and cooperating with the rear ends of the T-shaped members.

2. A detachable rubber heel comprising in combination with a metallic plate adapted to be secured to the leather heel of a shoe, inverted substantially T-shaped members secured to the bottom of the plate, channel members in said rubber heel adapted to slidably receive the T-shaped members, means for preventing the accidental displacement of the rubber heel from the leather heel, and to further lock the rubber heel in proper position on the leather heel, said means comprising a flat spring secured to the side of each of the channel members, the forward ends of the springs being disposed laterally to provide tongues adapted for engagement with the forward ends of the respective T-shaped members, and means cooperating with the rear ends of the T-shaped members for automatically moving the rubber heel with respect to the leather heel when the spring tongues are moved out of engagement with the forward ends of the T-shaped members to facilitate the removal of the rubber heel.

In testimony whereof we affix our signatures.

HENRY RINGLER.
HANS WILKINS.
